[57] CLAIM

The ornamental design for a transparent looseleaf page
for storing flexible, magnetic computer discs, substan-
tially as shown and described.

DESCRIPTION

FIG. 1 is a front perspective view of a transparent
looseleaf page for storing flexible magnetic computer
disks embodying my new design, and showing the
upper and lower front pockets in open condition;
FIG. 2 is a rear perspective view thereof, showing the
rear pocket in open condition;
FIG. 3 is an enlarged scale right side elevational view of
FIG. 1;
FIG. 4 is an enlarged scale left side elevational view
thereof;
FIG. 5 is a top plan view thereof;
FIG. 6 is a bottom plan view thereof;
FIG. 7 is a reduced scale front elevational view thereof
in closed condition;
FIG. 8 is a rear elevational view thereof; and
FIG. 9 is an enlarged scale cross sectional view taken
along line 9—9 of FIG. 7.
